*John B. Ferguson's Design, a Pattern
for Carpet.*

Patented Oct. 20. 1843.

No 13

*Sketch of Pattern No 13 designed by John B. Ferguson
of Thomastonville Conn.*

Des. 13

John P. Ferguson, Thompsonville, Let. —
Letters Patent No. 13, dated October 20. 1843. —

The Schedule referred to in these Letters Patent
and making part of the same. —

To all to whom it may concern. —

Be it known that I John P. Ferguson of Thompson

Dec. 13

At.

ville, in the County of Hartford and State of Connecticut, have invented or designed a new pattern or combination of figures to be worked into in grain Carpeting and I do hereby declare that the following is a full and exact description and to enable others skilled in the art to make and use my design, I describe the construction as follows.

A combi super in grain Carpet design drawn so as to be worked in various colours, but more especially in Maroon ground, with the two set figures worked in shot about yellow and white ground or green and white ground and the flowers chintzed with red or any other colours. The design, is known and denominated by the Thompsonville Carpet Manufacturing Company as pattern No. 6141.—

The main feature of it is that the warps of each figure do not interfere with one another - for instance, the yellow warp being on the right hand side of the carpet, and serving to bind the filling of the yellow and white set figure & the red warp on the left hand side serving to bind the filling of the red flowers, and green warp used to bind the filling of the green leaves. I distinguish this pattern from the common run of in grain patterns usually worked on the jacquard loom in the shading of the figures being worked up as much by the warp as the filling.

What I claim as my invention and desire to secure by letters patent is the peculiar combination of figures and the unusual form in which the figures are worked up in the carpet, the principal figure of which instead of being worked up in the centre as usual is formed on one side as an eccentric comb.
